United States Patent Office.

RUFUS DUTTON, OF BROOKLYN, NEW YORK.

Letters Patent No. 74,212, dated February 11, 1868.

IMPROVEMENT IN CUTTING-APPARATUS FOR HARVESTERS.

The Schedule referred to in these Letters Patent and making part of the same.

TO ALL WHOM IT MAY CONCERN:

Be it known that I, RUFUS DUTTON, of Brooklyn, in the county of Kings, and State of New York, have invented certain new and useful Improvements in the Construction and Combination of the Fingers, Leger-Plate, and Finger-Bars of Harvesting-Machines; and I do hereby declare that the following is a full, clear, and exact description thereof, and of their mode or manner of operation, reference being had to the accompanying drawings, and to the letters of reference marked thereon, and making a part of this specification.

The nature of my invention or improvements consists in a new construction and arrangement of the fingers and leger-plate of harvesting-machines, in combination with the finger-bar, whereby a lighter and stronger finger can be secured, and at a reduced cost.

Figure 1 is a sectional view of a finger and its leger-plate in combination with the finger-bar.

Figure 2 is a top view of fig. 1.

Figure 3 is a detached view of the leger-plate in figs. 1 and 2.

Figure 4 is a sectional view of a finger and its leger-plate, and of the finger-bar, the leger-plate slightly varying from the one shown in fig. 1.

Figure 5 is a top view of fig. 4.

Figure 6 is a detached view of the leger-plate in figs. 4 and 5.

My invention has reference to that class of fingers that have combined with or affixed to them a leger-plate for the knives to act against in cutting. Such plates, when used, have been and are most generally riveted to the finger. As this mode of fixing them together has a tendency to weaken the fingers, the latter are usually made larger and stronger than otherwise would be necessary. Such manner of fastening the leger-plate to the finger is, therefore, to be avoided if possible. Sometimes, also, the leger-plate is welded to the under surface of the slot of the finger, but as this method increases cost of construction, it is also to be avoided.

I obviate or overcome these objections in the following manner:

The main portion of the leger-plate is as broad as the under surface of the slot of the finger. The front end *c'* of such plate is made of a width less than that of the finger, and is shaped, as represented in fig. 3, so as to enter and fit in a recess, formed as shown by the dotted lines in figs. 2 and 5, made to receive it. The other end, *c*, of such leger-plate, instead of terminating at or about the commencement of the shank of the finger, and being riveted or welded thereto, is extended and bent, as shown in figs. 1 and 3, to correspond in shape with the under side of the finger-bar, and with the curved shank of the finger, and lies between the shank of the finger and the under side of the finger-bar, the extreme end of such plate fitting into a recess in the shank of the finger formed to receive it. The leger-plate when so constructed is placed in position before the finger-bar is secured to the finger, and is fastened and retained in position by the same rivet that secures the finger-bar and finger together.

The finger-bar represented in the drawings is turned up at its front edge, and is so combined or placed in connection with the finger that the leger-plate and the top surface of the turned-up edge of the finger-bar are on the same plane or level. When such a finger-bar is so combined with the fingers, the turned-up edge of the finger-bar forms a continuous guard or cross-bar for the knives to move upon.

The construction of leger-plate above described, and the manner of connecting it with the finger, may, however, be employed with finger-bars as ordinarily shaped. The construction and arrangement of leger-plate before described are specially adapted for use in connection with fingers made of malleable iron.

In converting cast into malleable iron, it is essential, to secure a complete and satisfactory operation or change, that the article or metal to be treated should not be very thick, as thick pieces are not likely to become wholly and sufficiently annealed entirely through.

By forming the leger-plate, and securing the same to the finger, as before mentioned, the finger can be made in skeleton-form, or hollow, as shown in figs. 1 and 3, whereby the several parts of the finger can be made thin and light enough to be wholly converted into malleable iron. If, however, the leger-plate were such as to be required to be riveted to the finger, the latter would necessarily have to be made solid or heavier at the back end of the slot, or in the shank, in order to secure sufficient strength for the rivet, and compensate for the rivet-hole, and such required thickness would interfere with the conversion of the finger into malleable iron.

But by the use of a leger-plate, as described, and so combined with the finger, the finger can be so shaped as to be more completely converted into malleable iron, and its strength thereby increased; and the finger can also be made lighter, thus securing or uniting both lightness and strength.

Such construction or form of leger-plate, and manner of securing it to the finger, also permits of a modification in shape of such leger-plate, by which a portion of such plate is made to act as a button, to hold down the front edge of the knife-bar, so that the knives will move in close contact with the leger-plate. Figs. 4, 5, and 6 represent such modification of form in the leger-plate, and illustrate its application in holding down the knife-bar.

In that portion of the leger-plate which passes under the finger-bar, as before described, and just at the end of the slot in the finger, is struck out or formed a tongue, D, which, however, is not bent down with the other portion of the leger-plate, but is left in the same plane with the main part of the leger-plate that covers the slot of the finger. This tongue D projects backward, and is made of such a length as to extend over the front edge of the finger-bar, and fits into a recess or groove made therein, as shown in fig. 4, such recess or groove being on the upper side of the knife-bar, and underneath the knife-blades or cutters. The leger-plate being firmly held down, and secured with the finger to the finger-bar by the bolt F, it will be at once apparent that the tongue D, which is a part of the leger-plate, will confine and hold down the knife-bar, and consequently the knives, upon the leger-plate; and as the knives or cutters entirely cover the tongue D, and the groove in which it moves, all danger of clogging is effectually prevented.

What I claim as my invention, and desire to secure by Letters Patent, is—

1. Fastening or securing the leger-plate between the finger and finger-bar, substantially as described, without the use of a separate rivet, or its equivalent, to fasten such leger-plate when the finger-bar is raised or turned up on its front edge to a level with the upper surface of the leger-plate, and so as to form the guard or cross-bar for the support of the knives.
2. Constructing the leger-plate so that a part thereof may pass between the finger and finger-bar, to hold such plate in position upon the finger, and a part thereof may pass over the knife-bar, to act as a button to hold down the front side of such bar, and keep the knives upon the leger-plate, substantially as and for the purpose set forth.
3. In combination with a leger-plate, constructed as described in the last claim, recessing the front edge of the finger-bar to receive the projecting part of the leger-plate, substantially as and for the purposes set forth.

R. DUTTON.
